UNITED STATES PATENT OFFICE.

WILLIAM J. WISE AND THOMAS O. ADAMS, OF NEW PHILADELPHIA, OHIO, ASSIGNEES
TO THE WISE-MCLUNG MANUFACTURING COMPANY, OF NEW PHILADELPHIA,
OHIO, A CORPORATION OF OHIO.

FAN FOR VACUUM CLEANERS.

Application filed November 23, 1921. Serial No. 517,399.

To all whom it may concern:

Be it known that we, WILLIAM J. WISE and THOMAS O. ADAMS, citizens of the United States, both residing at New Philadelphia, in the county of Tuscarawas and State of Ohio, have invented a new and useful Fan for Vacuum Cleaners, of which the following is a specification.

This invention relates to vacuum cleaners and more particularly to the construction and assembly of the fan upon the motor shaft. In the usual portable vacuum cleaner, the fan is located within a fan chamber having an inlet opening annularly aligned with the axis of the fan, the air being sucked into the fan chamber against the central portion of the fan and exhausted therefrom to the usual dust collector bag through an outlet opening disposed at one side of the periphery of the fan, and the objects of the invention are to provide a fan so constructed that the air may be exhausted from the fan chamber more rapidly than it is drawn into said chamber, in order to prevent any obstruction of the fan chamber; other objects being to provide means for conveniently assembling the fan upon the motor shaft.

The above and other objects may be attained by forming the body of the fan of convex or shallow conical shape, thus slightly restricting the central portion of the fan chamber adjacent to the point where the air is admitted thereto, allowing the air to be exhausted from the fan chamber more rapidly than it was drawn into said chamber.

The motor shaft may be shouldered and threaded upon its extremity, a flanged, shouldered fan hub being located thereon and carrying the fan which is held fixedly upon the motor shaft by means of a washer and nut placed over the threaded end portion of the shaft.

The invention thus set forth in general terms is illustrated in the accompanying drawings, in which—

Figure 1 is a plan view partly in section of a horizontal type of a portable vacuum cleaner provided with a fan embodying the invention;

Fig. 2, a section on the line II—II, Fig. 1;

Fig. 3, a perspective view of the end portion of the motor and shaft;

Fig. 4, a perspective view of the fan hub; 55

Fig. 5, a perspective view of the fan;

Fig. 6, a perspective view of the washer; and

Fig. 7, a perspective view of the nut which retains the fan upon the motor shaft. 60

Similar numerals of reference indicate corresponding parts throughout the drawings.

The motor 1, motor casing 2, fan casing 3, nozzle 4, wheels 5 and dust collector bag 6, may be of any usual construction, the air being drawn into the fan chamber 7 from the nozzle through the inlet opening 8, and exhausted therefrom into the dust collector bag through the outlet opening 9 in the manner customary in vacuum cleaners. 70

Although the invention is shown in the present case applied to a vacuum cleaner of the horizontal motor type, it will be understood that the invention is equally applicable without change to any other form of portable vacuum cleaner. 75

The motor shaft 10 is journaled in a bearing 11 carried in the base plate 12 of the motor frame, a felt packing 13 being preferably provided around the motor shaft within the cylindric opening 14 which contains the bearing for the purpose of preventing dust from working into the lower bearing and also of preventing lubricating oil from being carried downwardly along the shaft into the fan chamber. 85

The end portion of the motor shaft is reduced and threaded as at 15, providing an annular shoulder 16, the fan hub 17 being placed over the end portion of the shaft and provided with the internal shoulder 18 which engages the shoulder 16 of the shaft. 90

The fan hub 17 is provided midway of its length with the annular flange 19, and the annular body portion 20 of the fan, which is slightly convex or tapered, as best shown in Fig. 1, is provided with the central aperture 21 which fits snugly over the hub, the body portion of the fan being of suitable thickness to extend to the outer end of the hub. 95

The usual curved blades 22 are provided upon the fan, being preferably of greater width at their outer end portions than at the center of the fan, in order to quickly expel the air as it is drawn into the fan chamber through the inlet opening 8. 105

A washer 23 is placed over the end of the motor shaft and against the body portion 20 of the fan, a nut 24 being placed upon the threaded extremity of the shaft and tightened to hold the washer in frictional engagement with the fan, thus clamping the fan between the flange 19 of the hub and the washer 23, and clamping the fan hub tightly against the shoulder 16 of the shaft, the fan 10 thus being fixed upon the shaft.

As the body portion 20 of the fan is convexed or tapered toward the center, it will thus be evident that the central portion of the fan chamber is slightly restricted with 15 reference to the peripheral portion thereof, thus permitting the air to be expelled from the fan chamber more rapidly than it is drawn into said chamber, preventing any obstruction of the fan chamber and permitting 20 the air to be passed freely therethrough from the nozzle to the dust collector bag.

It will also be evident that the fan may be easily and readily assembled upon the motor shaft or removed therefrom, the loosening of the nut 24 allowing the entire fan 25 assembly to be slipped over the end of the motor shaft, while the fan may be held rigidly upon the motor shaft by tightening said nut.

30 We claim:—

1. In a vacuum cleaner including a fan chamber provided with an annular depression and having a central inlet opening and a

peripheral outlet opening, a rotary fan within the fan chamber comprising a concavo-convex disk having blades thereon, the disk being inclined away from the inlet opening from center to periphery, the periphery of the disk being located within said annular depression. 35

2. In a vacuum cleaner including a fan chamber provided with an annular depression and having a central inlet opening and a peripheral outlet opening, a rotary fan mounted within the fan chamber and comprising a saucer-shaped disk provided with transversely disposed blades the periphery of the disk being located within said annular depression. 40

3. In a vacuum cleaner including a fan 50 chamber, a motor and a motor shaft extending into the fan chamber, a reduced, threaded shank upon the motor shaft, an internally shouldered fan hub mounted upon said shank, a peripheral flange upon the hub, a 55 fan mounted upon the outer end portion of the hub and engaging said flange, a washer upon said shank engaging the fan, and a nut upon the shank engaging said washer whereby the fan is clamped between said 60 washer and hub flange.

In testimony that we claim the above, we have hereunto subscribed our names.

WILLIAM J. WISE.
THOMAS O. ADAMS.
